UNITED STATES PATENT OFFICE.

WILLIAM A. HESTER, OF EVANSVILLE, INDIANA.

POCKET FOR OVERALLS.

1,212,639.

Specification of Letters Patent. Patented Jan. 16, 1917.

Application filed October 29, 1915. Serial No. 58,596.

To all whom it may concern:

Be it known that I, WILLIAM A. HESTER, a citizen of the United States, residing at Evansville, in the county of Vanderburg 5 and State of Indiana, have invented certain new and useful Improvements in Pockets for Overalls, &c.; and I do hereby declare the following to be a full, clear, and exact description of the invention, such as will 10 enable others skilled in the art to which it appertains to make and use the same, reference being had to the accompanying drawings, and to the letters and figures of reference marked thereon, which form a part of 15 this specification.

This invention relates to new and useful improvements in pockets, especially adapted for use upon overalls and consists in the provision of a detachable pocket held to a 20 flap upon the overall by means of fasteners.

The invention comprises various details of construction, combinations and arrangements of parts which will be hereinafter fully described, shown in the accompanying 25 drawings and then specifically defined in the appended claim.

My invention is illustrated in the accompanying drawings, in which: Figure 1 is a plan view showing the application of the 30 pocket. Fig. 2 is a cross sectional view taken on line 2—2 of Fig. 1, and Fig. 3 is a detail perspective view of the pocket.

Reference now being had to the details of the drawings by letter, A designates overalls, and B is a flap projecting from the central band D, said flap being provided with eyelets F. A pocket, designated by letter H, which is of any shape or size, is provided with a flap N projecting above the upper 35 openings of the pocket and which is provided with eyelets R.

When it is desired to fasten the pocket in place, the two sets of eyelets are brought

into registration in pairs, and fasteners T, of any suitable kind such, for instance, as a paper fastener having two flexible shank portions, are inserted through the registering holes, said shank portions then being bent up against the inner face of the flap upon the pocket, thus securely holding the 50 same in place. When it is desired to remove the pocket, the shank portion of the fastener is bent out as will be understood and the pocket easily removed.

Upon reference to Fig. 2, it will be noted 55 that the supplemental pocket H is supported by the depending flap of the band and that the fastening means extends through the oppositely disposed overlapped flaps of said band and the supplemental pocket, so 60 that all strain and weight are carried by the band and not by the pocket proper, so that the weight of the articles carried in the pocket H in no wise affects the pocket proper, which latter is carried by the band 65 independent of the flap.

What I claim to be new is:—

In combination with overalls having a band with a depending intermediate flap having eyelets and a pocket supported from 70 said band, of a supplemental detachable pocket having a flap projecting above the opening in said pocket and having eyelets, and separable fastening devices passed through the eyelets in the overlapped flaps 75 and securing the flaps together in overlapped condition, said fastening means being independent and disconnected from the pocket proper.

In testimony whereof I hereunto affix my 80 signature in presence of two witnesses.

WILLIAM A. HESTER.

Witnesses:

CLARA F. HELFRICH,
MAMIE A. LAMBERS.
